UNITED STATES PATENT OFFICE.

MAX TRUETZSCHLER, OF BRIDGEPORT, CONNECTICUT.

MECHANICAL ADVERTISING DEVICE.

1,187,113.

Specification of Letters Patent. Patented June 13, 1916.

Application filed November 17, 1915. Serial No. 61,869.

To all whom it may concern:

Be it known that I, MAX TRUETZSCHLER, a citizen of the United States, residing at the city of Bridgeport, county of Fairfield, State 5 of Connecticut, have invented certain new and useful Improvements in Mechanical Advertising Devices; and I do declare the following to be a full, clear, and exact description of the invention, such as will enable 10 others skilled in the art to which it appertains to make and use the same.

This invention relates to certain new and useful improvements in mechanical advertising devices and particularly to such devices adapted for performing tricks on the 15 magician style.

The primary object of the invention is to provide an efficient device or mechanism of the above character for operating automatically to display and remove from display, alternately, any desired article such as an 20 advertisement.

The invention further resides in providing a table, or other support, with an article 25 removably disposed thereon, a figure, such as a man, arranged by the table, and mechanism for associating the movements of the figure with those of the article whereby to resemble a magician performing an act.

Further, the invention resides in the salient features of construction and combinations of parts hereinafter described and 30 claimed, reference being had to the accompanying drawings wherein:

Figure 1 is a front elevation of the improved advertising device with the front wall removed to show the working mechanism; Fig. 2 shows, in pictures, the sequence 35 of operations in the magical appearance and disappearance of the article; Fig. 3 is a horizontal section on line 3—3 of Fig. 1 through the working mechanism; Fig. 4 is a vertical section on line 4—4 of Fig. 1 disclosing the table and mounting for the display article; Fig. 45 5 is a similar view taken about on line 5—5 of Fig. 1 showing the figure and its operating mechanism in elevation; Fig. 6 is a rear elevation of the device illustrating the drive for the working mechanism; Fig. 50 7 is a transverse section through the table on line 7—7 of Fig. 4; and Fig. 8 is a detailed fragmentary section of the mechanism for actuating an arm of the human figure.

The mechanical advertising device is conveniently housed in a casing 1 having a plat-

form 2 designed to represent a stage and also to conceal the operating or working mechanism, the walls 3 of the casing being suitably decorated as the stage background.

On the stage is a human figure 4, dressed 60 to resemble a magician, a table 5 and a screen 6. The table has a central opening 7 and between its legs 8 are mirrors 9 angularly related and intended to reflect the screen for giving the impression that the observer 65 is looking between the table legs at the back of the screen.

The display or advertising article is here shown as a bottle 10 secured to a cap plate 11 of a vertically movable rod 12 and adapted 70 to be projected through the table opening 7, to appear as being seated on the table, or withdrawn to be hidden by the mirrors 9.

In the compartment 13, below the stage, the operating mechanism is supported on a 75 base plate 14 upward from which extend standards 15 having bearings 16 for the shaft 17. On one standard is a fixed bracket 18 to which is pivoted a follower lever 19 carrying a follower roller 20 on one end and 80 having its opposite end guided in a vertical slot of a bracket 21 and pivotally secured to the end of the vertically movable rod 12 that extends through the aperture 2' of the platform by a universal connection 22. The follower 85 20 co-operates with a cam 23 fixed on the rotary shaft 17 whereby on rotation of the latter the cam will oscillate the lever 19 and intermittently project and withdraw the bottle 10.

Spaced from cam 23 on the shaft is a fixed double cam 24 having oppositely extending throw portions 25 arranged in alternation, each throw portion including a long rest section 26. Straddling the double cam 24 for 95 co-operation therewith is the forked end 27 of a lever 28 pivoted between its ends for oscillatory movement on a standard 29, the opposite end of said lever carrying a segmental gear 30 for rotating a gear 31 with 100 which it meshes. This gear 31 is provided with a pair of pins 32 for interlocking in corresponding slots formed in the lower end of a tubular and rotatable pedestal or shaft 33. A disk 34, fixed to the upper end of 105 shaft 33, has the left foot 35 of the toy figure 4 secured thereto whereby on rotation of the shaft the figure will turn, the right foot being free of the platform 2 to move with the figure. The throw of the double cam is suffi- 110

cient to turn the figure approximately one quarter turn, from a full front to a side position and vice versa, as depicted in Fig. 2. A stand 36 on the base plate 14 is formed with a bearing shoulder 37 which supports the gear 31 and its shaft 33 for rotation. An integral rod 38 extends upwardly from the stand 36 through the gear and shaft and also the left leg of the toy figure terminating within the hollow body of the latter. On this terminal of the rod 38 is fixed an angular arm 39 which, when the toy figure is turned, will be engaged by a crank arm 40 of a rock shaft 41 journaled in a shoulder bearing 42, said bearing having the left arm 43 of the toy figure secured to the outer end thereof. The arms 39 and 40 are so related that the latter will ride up or along the former and, consequently, swing the arm 43 of the toy figure from a vertical to substantially a horizontal position. In the hand of the swinging arm is carried a placard or shield 44, upon which may be arranged suitable advertising matter, as shown in Fig. 2, the function of such placard being to hide or conceal the table top from view during the projection and withdrawal of the bottle for rendering the operation magical in appearance.

The cams 23 and 24 are so positioned and related that the figure is turned and the placard elevated to hide the table before the bottle is initially moved to or from a display position.

Assuming the parts to be in the position designated A, Fig. 2, in which the cam 23 is retaining the bottle elevated. Upon rotation of the shaft 17, the double cam will oscillate the lever 28 thereby rotating the toy figure to face the table during which movement the coacting arms 39 and 40 will swing the arm and placard or concealing element 44 to the position shown at B. While the fork 27 is riding on rest portion 26, the follower 20 rides off cam 23 and, thus, lowers the bottle behind the mirrors 9. The fork then rides off one cam portion to an opposite throw cam portion, returning the figure and arm, with its placard, to normal position indicated at C. Continued rotation of the shaft moves the figure to the position at D where the follower 20 rides onto cam 23 and elevates the bottle after which the figure is lowered and the appearance will be as indicated at A.

For rotating the shaft 17, a gear 45 is fixed thereon with which meshes a worm 46 carried on a transverse shaft 47, the latter being journaled in a bearing 48 of standard 49 and also in the rear wall of the casing 1. On the projecting end of shaft 47 is fixed a gear 50 having a handle 51 for manual rotation, as for demonstration purposes, the preferable drive for exhibition being a motor, not shown, connected with a pulley 52

fixed on a counter shaft 53. The latter is provided with a worm 54 adapted to mesh with the gear 50. The shaft 53 is swingingly mounted in a bearing 55, and the worm is retained in meshing relation with the gear by a fixed bearing 56 supporting the shaft 53, said fixed bearing being removable whereby the worm may be swung out of mesh with gear 50 to permit of manual rotation of the latter. The pivotal bearing 55 is supported by a stop 57 when the worm 55 is out of mesh with gear 50.

It is, of course, understood that any desired article may be substituted for the bottle 10 and various other changes made without departing from the spirit of the invention.

What is claimed is:

1. In a mechanical advertising device, a table having a top formed with an opening, 85 a vertically movable member arranged beneath the table opening, a display article operable by the member for movement through the table opening, and a mirror enclosure beneath the table top. 90

2. In a mechanical advertising device, a casing having a platform, a table supported by its legs on the platform and having an opening in its top, a vertically movable rod 95 slideable through an opening in the platform beneath the table opening, a display article carried on the upper end of the rod for movement through the table opening, mirrors between the table legs to hide the rod, a screen partly surrounding the table to be 100 reflected by the mirrors, and means for operating the rod to project the display article above the table.

3. In a mechanical advertising device, a casing having a platform, a table supported 105 by its legs on the platform and having an opening in its top, a vertically movable rod slideable through an opening in the platform beneath the table opening, a display article carried on the upper end of the rod for 110 movement through the table opening, mirrors between the table legs to hide the rod, a screen partly surrounding the table to be reflected by the mirrors, a rotary shaft, a cam fixed on the latter, and a follower lever 115 coöperating with the cam and operatively connected to the rod for moving the latter vertically.

4. In a mechanical advertising device, a casing having a platform, a table supported 120 by its legs on the platform and having an opening in its top, a vertically movable rod slideable through an opening in the platform beneath the table opening, a display article carried on the upper end of the rod for 125 movement through the table opening, mirrors between the table legs to hide the rod, a screen partly surrounding the table to be reflected by the mirrors, a rotary shaft, a cam fixed on the latter, a follower lever co- 130

operating with the cam and operatively connected to the rod for moving the latter vertically, and concealing means operable by the shaft for movement in advance of the table to hide the top during movement of the display article through the table opening.

5. In a mechanical advertising device, a casing having a platform, a table supported by its legs on the platform and having an opening in its top, a vertically movable rod 10 slidable through an opening in the platform beneath the table opening, a display article carried on the upper end of the rod for movement through the table opening, mirrors 15 between the table legs to hide the rod, a screen partly surrounding the table to be reflected by the mirrors, a rotary shaft, a cam fixed on the latter, a follower lever co-operating with the cam and operatively connected to the rod for moving the latter vertically, a toy figure on the platform, and means for turning the figure to and from a position facing the table.

6. In a mechanical advertising device, a casing having a platform, a table supported by its legs on the platform and having an opening in its top, a vertically movable rod 25 slidable through an opening in the platform beneath the table opening, a display article carried on the upper end of the rod for movement through the table opening, mirrors between the table legs to hide the rod, a screen partly surrounding the table to be reflected by the mirrors, a rotary shaft, a cam fixed on the latter, a follower lever co-operating with the cam and operatively connected to the rod for moving the latter vertically, a toy figure on the platform, a concealing element carried by the figure, and 30 means for turning the figure to and from a position facing the table to position the concealing element in front of the latter.

7. In a mechanical advertising device, a casing having a platform, a table supported by its legs on the platform and having an opening in its top, a vertically movable rod 45 slidable through an opening in the platform beneath the table opening, a display article carried on the upper end of the rod for movement through the table opening, mirrors between the table legs to hide the rod, a screen partly surrounding the table to be reflected by the mirrors, a rotary shaft, a cam fixed on the latter, a follower lever co-operating with the cam and operatively connected to the rod for moving the latter vertically, a toy figure on the platform, means for turning the figure toward and from the table, an arm carried by the figure 50 for swinging forwardly from the side of the latter, a placard carried by the arm adapted to be swung with the arm in front of the table, and means for swinging the arm.

8. In a mechanical advertising device, a casing having a platform, a table supported

by its legs on the platform and having an opening in its top, a vertically movable rod 70 slidable through an opening in the platform beneath the table opening, a display article carried on the upper end of the rod for movement through the table opening, mirrors between the table legs to hide the rod, a screen partly surrounding the table to be reflected by the mirrors, a rotary shaft, a cam fixed on the latter, a follower lever co-operating 75 with the cam and operatively connected to the rod for moving the latter vertically, a toy figure on the platform, means for turning the figure toward and from the table, an arm carried by the figure for swinging forwardly from the side of the latter, a placard carried by the arm adapted to be swung with the arm in front of the table, and means for swinging the arm by and during turning movement of the figure.

9. In a device of the character described, a table, a display article, means for intermittently moving the article to and from the table, a toy figure normally facing at an angle from the table and adapted to be moved to face the table, and means for moving the figure during the rest periods of the article.

10. In a device of the character described, a table, a display article, means for intermittently moving the article to and from the table, a rotatable toy figure, a concealing element adapted for movement in front of the table prior to movement of the display article, and means for rotating the concealing element and figure during the rest periods of the display article.

11. In a device of the character described, a table, a display article, means for intermittently moving the article to and from the table, a toy figure, a swingingly carried arm on the figure, a shield carried by the arm and adapted to conceal the table during movement of the display article, and means for moving the arm during rest periods of the article.

12. In a device of the character described, a table, a display article, means for intermittently moving the article to and from the table, a toy figure, a swingingly carried arm on the figure, a shield carried by the arm and adapted to conceal the table during movement of the display article, means for moving the body of the figure during rest periods of the display article, and means for swinging the arm by and during movement of the figure.

13. In a mechanical advertising device, a hollow toy figure movably mounted, an arm therefor, a rock shaft journaled in the figure and carrying the arm, and a fixed member terminating within the figure, said shaft having a crank arm within the figure adapted to engage and ride said member during movement of the figure.

14. In a mechanical advertising device, a

5 rotatable element, a toy figure carried thereby, a fixed rod extending within the figure and having a fixed arm, a rock shaft journaled in the figure and having a crank arm adapted to ride on the fixed arm to impart rotary movement to the shaft on movement of figure, and an arm of the figure carried by the shaft to move therewith.

10 15. In a mechanical advertising device, a gear, a tubular element carried thereby, a toy figure fixed to the element, a rock shaft journaled in the figure and having a crank arm, an arm of the figure carried by the shaft for movement therewith, a stand supporting the gear for movement, and a rod on the stand extending upwardly through the tubular element and figure and provided with a fixed part on which the crank arm is adapted to ride during movement of the figure to rotate the shaft and swing the arm.

15 20 25 16. In a device of the character described, a support, a table thereon, a reflective surface depending from the table top, a display article, and means operable in rear of the reflective surface for moving the article from behind the surface to the table top.

20 25 30 35 17. In a device of the character described, an angular reflective surface, a table having legs between which the surface is disposed, a screen positioned behind and at the side of the reflective surface to be reflected thereby, an article movable from behind the reflective surface to the table, means for intermittently moving the article, and other means to conceal the table top only during movements of the article.

Copies of this patent may be obtained for five cents each, by addressing the "Commissioner of Patents, Washington, D. C."

18. In a mechanical advertising device, a display article, a table, means for intermittently moving the article to and from the table, a toy figure normally facing away from the table and adapted to be moved to face the table, a concealing element adapted to be moved to conceal the article when the figure is moved to face the table, and means operable for moving the figure and the concealing element, said last means operating alternately relative to the first means.

19. In a mechanical advertising device, a display article, a table, means for intermittently moving the article to and from the table, a toy figure normally facing away from the table and adapted to be moved to face the table, a concealing element normally carried at the side of said figure and adapted to be moved to conceal the article when the figure is moved to face the table, and means operable alternately relative to the first means to move the figure and concealing element.

20. In a mechanical advertising device, a casing having a platform, a table on the platform, a display article mounted for movement to and from the table, a toy figure rotatably mounted on the platform, and operating mechanism beneath the platform for moving the article and rotating the figure alternately.

In testimony whereof I affix my signature in presence of two witnesses.

MAX TRUETZSCHLER.
